UNITED STATES PATENT OFFICE

MANUEL D. AVILLAR, OF NEW YORK, N. Y.

DESIGN FOR A BOTTLE-SEAL OPENER

Application filed May 25, 1929. Serial No. 31,402. Term of patent 7 years.

To all whom it may concern:

Be it known that I, MANUEL D. AVILLAR, a citizen of the United States, and resident of New York city, in the county of New York and State of New York, have invented a new, original, and ornamental Design for a Bottle-Seal Opener, of which the following is a specification, reference being had to the accompanying drawings, forming part hereof.

I claim:

The ornamental design for a bottle seal opener as shown.

MANUEL D. AVILLAR.
